EMILE GIRARDEAU AND JOSEPH BETHENOD, OF PARIS, FRANCE.

DEVICE FOR AUXILIARY STARTING FOR HIGH-POWER RADIOTELEGRAPHIC STATIONS.

1,312,972.

Specification of Letters Patent. Patented Aug. 12, 1919.

Application filed March 16, 1916. Serial No. 84,668.

To all whom it may concern:

Be it known that we, EMILE GIRARDEAU and JOSEPH BETHENOD, residing in Paris, France, 10 Rue Auber, have invented a new 5 and useful Improvement in Devices for Auxiliary Starting for High-Power Radiotelegraphic Stations.

Auxiliary excitation systems in radiotelegraphy are known, their object being to 10 regulate the discharge in the main oscillating circuit of high power radio-telegraphic apparatus.

The present invention relates to improved means whereby suitable excitation of the 15 auxiliary circuit is effected from a source of alternating current of high frequency preferably of 500 to 1000 periods. The means hereinafter described have the advantage of being capable of adaptation generally without 20 it being necessary to provide an auxiliary source for the excitation, the auxiliary spark gap being fed by the main source. Moreover, the auxiliary spark gap is discharged at low power about 6% of that of 25 the main discharge and is not traversed by the main current.

The accompanying drawing illustrates, by the way of examples, two embodiments of the invention: Figure 1 is a circuit diagram 30 illustrating a system of generating electric waves for wireless telegraphy, and Fig. 2 is a diagram of a slightly modified system; C is the condenser of the main oscillating circuit and is charged at high tension by 35 means of a transformer T, the primary winding of which is fed by the alternating current generator A in accordance with any known method; the main spark gap E of known type, is adjusted so that the maximum voltage at the terminals of the 40 condenser C is insufficient to produce alone an oscillating discharge in the circuit C E S.

In order to obtain the spark discharge at E at very regular intervals, a circuit K r l 45 is provided in parallel with the condenser C, K being a capacity, r an adjustable ohmic resistance and l an adjustable inductance. Owing to the provision of this circuit the charge of the condenser K may be slightly 50 in advance of that of the condenser C. An adjustable inductance s is connected inductively with the inductance S. If an auxiliary spark gap indicated at e is suitably adjusted the oscillating discharge of K through 55 the inductance s produces in the inductance S an induced voltage which is added at E to

that producer by the transformer at the terminals of the condenser C; the discharge at E thus being effected at the precise moment when the voltage at C is at its maximum, 60 if the constant dimensions of the different circuits are suitably chosen. The auxiliary spark gap e is preferably of the rotary type; it might include the spark electrodes between which a disk provided with diametrically opposite projecting points rotates; the movable disk may be driven indirectly through the medium of suitable gearing from the alternating current generator A as indicated by the gears R and P. This solution is advantageous in view of the moderate power for the production of the auxiliary spark. The higher the circumferential speed of this disk the smaller the diameter of the disk may be held. This gear 70 transmission necessitates a certain amount of play between the toothed wheel R keyed on the alternator shaft and the pinion P keyed on the shaft of the spark gap e; it follows therefore that the phase of the spark 75 relative to the voltage at the terminals of the condenser C with respect to the times when the sparking distances are at a minimum at e, may vary with the reduction in speed of the alternator. Owing to its comparatively high inertia, the rotary spark gap disk tends to oppose a decrease in speed more particularly those due to variations of the periodic charges during emission, and it is difficult to completely avoid this. In 80 order to eliminate this disadvantage which may render the operation of the auxiliary spark gap very irregular, it is advisable to counterbalance the tendency of the rotary disk to pick up speed in the periods of spark 85 discharge in the main spark gap.

The simplest solution is then to couple or connect the rotary disk with a generator D. This generator may be functionally associated with the generator A and may supply the direct current for the field of the main alternator. It is obvious that the load of this generator will, if necessary, be increased automatically at each emission of a signal, that is to say at each decrease of the 90 speed of the main alternator. It is well known in the art of wireless telegraphy to regulate the transmission of signals by varying the field current of the alternating current generator which is used as a source of 95 energy.

The function of the inductance 1 which

may comprise iron, is very important, on the one hand it limits to the desired extent the energy stored in the auxiliary condenser K whatever the capacity of the latter may be; on the other hand it prevents a short-circuit which would have a deleterious effect on the condenser C when the spark gap e is operative. The resistance r of the charging circuit $r l K$ may be increased so as to produce a slight lead of the charge on the condenser K over that of C, and thereby overcome the slight interval necessarily existing between the operations of the spark gaps e and E. In all cases, one would not think of eliminating the inductance l by considerably increasing r and the use of this inductance for the above mentioned purpose constitutes a feature of the present invention.

It should be noted that the lengths of the waves of the oscillating circuits E C S and e k s are not necessarily the same; the waves of the latter circuit may be selected shorter or longer than those of the main circuit, according to local requirements.

Although it has been stated above that the period of oscillation proper of the auxiliary excitation circuit may be selected arbitrarily with respect to that of the main circuit, the phenomenon observed in circuits coupled in resonance may be utilized in order to obtain an auxiliary voltage, as high as desired, at the terminals of the main spark gap. An important practical advantage is obtained which results in a reduction in the ratio of transformation and the coupling co-efficient of the transformer between the auxiliary circuit and the main circuit, without interfering with the efficiency of excitation. For this purpose we arrange, as shown in Fig. 2 an auxiliary capacity K', in shunt to the terminals of the main spark gap E. As long as the spark gap E is inoperative a closed oscillating circuit S C K' S, is thereby produced, having a predetermined periodicity, which it is possible to synchronize with the excitation circuit K s e. When the latter is rendered operative and if the constant dimensions are well selected, a high tension or voltage is produced at the terminals of K' and consequently at E so that the circuit S C K' acts with regard to the circuit K s e as an artificial antenna having a capacity substantially equal to that of K'. K' is so selected, as to be of low capacity in comparison with that of the main condenser C so as to limit the energy accumulated in the said capacity K' which would be uselessly spent in the spark gap E when the latter is rendered operative.

A capacity K'' may be provided across the terminals of s.

This allows for the provision of a local circuit s K'' s the period of which can always be synchronized with that of the cir-

cuit S C K' S. This arrangement may be employed when the length of connections between s and e is considerable (as it may be in some stations) in order to permit of ready synchronization of the circuits e K s e 70 and S C K' S. It will be understood that it is the discharge of the condenser K through e that produces the vibration of the local circuit s K'' s by a phenomenon of impulsion analogous to that used in apparatus called "wave controllers" for controlling receivers.

We claim:

1. A system for generating waves for wireless telegraphy, comprising a principal 80 oscillation circuit including a source of energy, a spark gap, a condenser, an inductance; and an auxiliary generating circuit also including a spark gap, a condenser and an inductance, the inductance of the auxiliary circuit being influenced by that of the principal circuit, and the condenser of the auxiliary circuit in serial connection with a resistance and inductance being shunted to the condenser of the main circuit. 90

2. A system for generating waves for wireless telegraphy, comprising a principal oscillation circuit including a source of energy in the form of an alternating current generator, a spark gap, a condenser, an inductance; an auxiliary generating circuit including a condenser, an inductance and a spark gap which consists of a pair of spark electrodes and a rotary element between the same, the rotary element being mechanically connected with the said generator, the inductance of the auxiliary circuit being influenced by that of the principal circuit, and the condenser of the auxiliary circuit being charged by the same source of energy from 100 which the principal circuit derives its energy, and a resistance in series with an inductance placed between the source of energy and the condenser of the auxiliary circuit. 110

3. A system for generating waves for wireless telegraphy, comprising a principal oscillation circuit including a source of energy in the form of an alternating current generator functionally associated with a dynamo 115 electric machine generating the current for the field of said alternating current generator, a spark gap, a condenser, an inductance; and an auxiliary generating circuit including a condenser, an inductance, a rotary element provided with projections, and a spark gap formed by a pair of electrodes between which said rotary element is moved so as to bring intermittently its projections into opposition to said electrodes, said rotary element being driven from the shaft of the alternating current generator, and being mechanically connected with the said field current generator, the inductance of the auxiliary circuit being influenced by that of 120 125 130

- the principal circuit, and the condenser of the auxiliary circuit being charged by the source of energy of the principal circuit, a resistance in series with an inductance being placed between the condenser of the auxiliary circuit and said source of energy. 5
4. A system for generating waves for wireless telegraphy, comprising a main oscillation circuit containing a source of energy in form of an alternator functionally associated with a direct current generator producing the field current for the alternator, a spark gap, a condenser, an inductance; and an auxiliary generating circuit comprising a condenser, an inductance, a pair of electrodes, a rotary element provided with projections movable between said electrodes to produce intermittently a spark gap, said rotary element being actuated by means of transmission gears from the shaft of the alternator, the field current generator for the alternator being mounted on the shaft on which the rotary element for the spark gap of the auxiliary circuit is mounted, the inductance of the auxiliary circuit being influenced by that of the principal circuit, and the condenser of the auxiliary circuit being charged by the same source of energy from which the main circuit is charged, a resistance in series with an inductance being placed between the source of energy and the condenser of the auxiliary circuit. 10 15 20 25
5. A system for generating waves for radio telegraphy, comprising in combination a main oscillation circuit containing a spark gap, a condenser, and an inductance; and an auxiliary generating circuit comprising also a spark gap, an inductance, and a condenser connected with the electrodes of the spark gap, the inductance of the auxiliary circuit being influenced by that of the main circuit, and the condenser of the auxiliary circuit being charged directly from the source for the main circuit through a resistance and inductance which are placed in series with the auxiliary condenser, said last named condenser, resistance, and inductance being connected across the main circuit. 30 35 40 45
6. A system for generating waves for radio telegraphy, comprising a principal oscillation circuit containing a source of electrical energy, a spark gap, a condenser, an inductance; and an auxiliary generating circuit comprising also a spark gap, an inductance, and a condenser, the electrodes of the auxiliary spark gap being connected with the condenser and auxiliary inductance, the inductance of the auxiliary circuit being influenced by that of the principal circuit, and the condenser of the auxiliary circuit being directly charged from the same source from which the principal circuit derives its energy, but through the intermediary of a resistance and an inductance which are placed in series. 50 55 60 65
7. A system for generating waves for wireless telegraphy, comprising a principal oscillation circuit which includes a source of energy, a spark gap, a condenser, an inductance; and an auxiliary generating circuit also including a spark gap, a condenser, and an inductance, the inductance of the auxiliary circuit being influenced by that of the principal circuit, the condenser of the auxiliary circuit being charged from the same source from which the principal circuit derives its energy, a resistance in series with an inductance being interposed between the source of energy and the condenser of the auxiliary circuit, and a second condenser 70 75 80 in the auxiliary circuit being shunted across the inductance of the auxiliary circuit. 85
8. A system for generating waves for wireless telegraphy, comprising a principal oscillation circuit which includes a source of energy, a spark gap, a main condenser, an inductance, and a second condenser shunted to the electrodes of the main spark gap; and an auxiliary generating circuit also including a spark gap, a condenser, and an inductance, the inductance of the auxiliary circuit being influenced by that of the principal circuit, the condenser of the auxiliary circuit being charged from the same source from which the principal circuit derives its 90 95 energy, a resistance in series with an inductance being interposed between the source of energy and the condenser of the auxiliary circuit, and the auxiliary circuit including an additional condenser shunted across the 100 inductance of the auxiliary circuit. 100
